(57) **CLAIM**

The ornamental design for a cap of a cooking utensil, as shown and described.

DESCRIPTION

FIG. 1 is a top and side perspective view of a cap for a cooking utensil showing my new design;

FIG. 2 is a side elevational view thereof, the side opposite that shown in FIG. 2 being the mirror image thereof;

FIG. 3 is a side elevational view thereof taken from the left of FIG. 2;

FIG. 4 is a side elevational view thereof from the right of FIG. 2;

FIG. 5 is a top plan view thereof; and,

FIG. 6 is a bottom plan view thereof.
